Brown & Ward

UNITED STATES PATENT OFFICE.

HARRY P. MACDONALD, OF JERSEY CITY, NEW JERSEY.

BOOK-SHELF.

SPECIFICATION forming part of Letters Patent No. 791,153, dated May 30, 1905.

Application filed April 29, 1904. Serial No. 205,446.

To all whom it may concern:

Be it known that I, HARRY P. MACDONALD, a citizen of the United States, and a resident of Jersey City, in the county of Hudson and State of New Jersey, have invented a new and useful Improvement in Book-Shelves, of which the following is a specification.

My invention relates to an improvement in book-shelves, and has more particularly for its object to provide certain improvements in the construction, form, and arrangement of the several parts with respect to each other whereby a very strong and light shelf may be formed capable of withstanding the weight of books placed thereon.

A further object is to provide a shelf of the above character which will be extremely cheap to manufacture and in which the parts are easily assembled.

A practical embodiment of my invention is represented in the accompanying drawings, in which—

Figure 1 is a top plan view of a portion of one form of shelf. Fig. 2 is an end view; Fig. 3, a transverse section; Fig. 4, a side view; Fig. 5, a longitudinal section; Fig. 6, a partial top plan of the blank from which one of the longitudinal bars is formed, and Fig. 7 is a plan view of the blank from which one of the transverse end bars is formed.

In the form shown each transverse bar is formed from a blank of sheet metal so shaped that when the blank is bent to complete the end bar the said end bar will have a vertical portion 1, a lip 2 extended inwardly from its lower edge, and a plurality of flaps 3, bent downwardly from the upper edge of the vertical portion 1, each flap provided with two inwardly-bent wings 4. Each longitudinal bar is formed from a blank which is so shaped that when the bar is completed it will have a horizontal portion 5, provided with downwardly-extended sides 6 7, having upwardly-turned lips 8 9, the horizontal portion 5 having downwardly-turned flaps 10 11 at its ends. The transverse bars may further be provided with extensions 12, fitted to

fold inwardly along the outer side of the outermost longitudinal bar.

When the shelf structure is set up, the adjacent wings 4 of two flaps 3 are embraced between the lips 8 and 9 and the sides 6 and 7 of one of the longitudinal bars. The lip 2 of each transverse bar extends beneath the lower edges of the sides of the longitudinal bars. The flaps 10 and 11 at the ends of each longitudinal bar are folded down over the outer faces of the transverse bars. This makes a very strong shelf structure.

What I claim is—

1. A book-shelf comprising transverse bars and longitudinal bars, each transverse bar having a vertical portion, and a plurality of flaps bent downwardly from the upper edge of the vertical portion, each flap provided with two inwardly-bent wings.

2. A book-shelf comprising transverse bars and longitudinal bars, each transverse bar having a vertical portion, a lip extended inwardly from its lower edge, and a plurality of flaps bent downwardly from the upper edge of the vertical portion, each flap provided with two inwardly-bent wings.

3. A book-shelf comprising transverse bars and longitudinal bars, the transverse bars having downwardly-turned flaps located between the longitudinal bars and inwardly-bent wings located within the longitudinal bars.

4. A book-shelf comprising transverse bars and longitudinal bars, the longitudinal bars having downwardly-extended sides and upwardly-turned lips, the transverse bars having downwardly-turned flaps located between the longitudinal bars and inwardly-bent wings located between the sides and upwardly-turned lips of the longitudinal bars.

5. A book-shelf comprising transverse bars and longitudinal bars, the transverse bars having inwardly-turned lips beneath the longitudinal bars, downwardly-turned flaps between the longitudinal bars and inwardly-bent wings within the longitudinal bars.

6. A book-shelf comprising transverse bars

and longitudinal bars, the transverse bars having downwardly-turned flaps between the longitudinal bars and inwardly-bent wings within said bars, the longitudinal bars having end flaps bent downwardly over the outer faces of the transverse bars.

In testimony that I claim the foregoing as

my invention I have signed my name, in presence of two witnesses, this 13th day of April, 1904.

HARRY P. MACDONALD.

Witnesses:

FREDK. HAYNES,
C. S. SUNDGREN.
